CLAIM

The ornamental design for an analysis device, as shown and described.

DESCRIPTION

FIG. 1 is a top, front, left side perspective view of an analysis device showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a top, rear, right side perspective view thereof.
The broken lines depict portions of the analysis device that form no part of the claimed design.
